MARTIN L. PATTERSON, OF BOGOTA, NEW JERSEY, ASSIGNOR TO THE SPERRY GYROSCOPE COMPANY, OF BROOKLYN, NEW YORK, A CORPORATION OF NEW JERSEY.

ARC LAMP.

Application filed March 16, 1922. Serial No. 544,191.

This invention relates to arc lamps, and more particularly to means for extinguishing the arc and stopping its operating mechanism when one or both of the electrodes has 5 stopped feeding.

In modern arc lamps, and especially those used in searchlights or in motion picture projecting apparatus, the arc electrodes are fed through their respective holders rather 10 than advancing the holders with the electrodes. Also, preferably, a separate feed is provided for each electrode, the negative feed being automatically controlled in accordance with the arc potential, i. e., arc 15 length, as determined by the positions of the arcing tips of the electrodes and the positive electrode feed being governed by the position of its arcing end. Such a feed has a serious effect, however, i. e., when the 20 outer end of an electrode has passed beyond the means for feeding it through the holder, no further feeding takes place, the inner end or tip may continue to burn away until, if not watched, it will burn back into the metallic holder and arcing will take place 25 between the holder and the opposite electrode, thus causing damage to, or destruction of the holder.

It is one object of the present invention 30 to provide means for automatically extinguishing the arc when one or both of the electrodes stop feeding, because of having passed beyond their feeding means.

Other objects and advantages will herein- 35 after appear.

In the accompanying drawings wherein I have shown what I now consider to be the preferred embodiment of my invention,

Fig. 1 is a side elevation, partly in sec- 40 tion, of a searchlight mechanism, including a wiring diagram.

Fig. 2 is a side sectional view of the positive electrode supporting head and the means for controlling the position of said electrode. 45

Fig. 3 is an end section of the positive feed mechanism.

In the drawing there is shown a control box 10 slidably mounted by projections 11 operating in guide-slots 12 in the side-walls which extend downwardly from the drum of the light. Upon box 10 are mounted the supports 15 and 16 for the negative carbon-holder 17 and the positive carbon-holder 18, respectively. Within the control box 10 is

mounted the mechanism for controlling the feeding of the carbons 19 and 20, and for a full disclosure of said mechanism, reference is made to the patent to Elmer A. Sperry, No. 1,362,575, granted December 14, 1920. 60

It may be briefly stated however, that the negative carbon is held between rollers 21 on opposite sides thereof and that said rollers are operated to feed the carbon in one direction or the other by means of gearing 22, 23, 24 operated by a rod 25 connected by a link 26 and gearing 27, 28 to ratchet-wheels 29 and 30, having oppositely disposed teeth. Said ratchet-wheels are mounted on a fixed shaft 31, but pawls 32 and 33 cooperating with ratchet-wheel 29 and pawls 34 and 35 cooperating with ratchet-wheel 30 are mounted upon a slide 40 which is reciproated by a bar 41 operated by a motor 100 and other mechanism (not shown), the shaft 31 operating in a slot 39 in the wall of slide 40. The pawls are normally held out of contact with the ratchet-wheels by links 42 and 43 fixed to opposite arms of a lever 44 to the end of one of which arms is pivoted the core 45 of a solenoid 46. The solenoid is of such strength that its magnetism is sufficient to draw upon core 45 to counter-balance a spring 47 when the arc is of proper length and voltage, but as the arc 85 lengthens due to burning away of the carbons, the voltage increases, the core 45 is more strongly attracted by the solenoid and lever 44 is tilted to bring one set of pawls into engagement with their corresponding ratchet-wheel. With each reciprocation of slide 40, said ratchet-wheel will be operated to feed the negative carbon toward the positive carbon. When the proper voltage is established, core 45, lever 44, and hence the set of operating pawls will move back to counter-balanced position. Should the voltage fall below the predetermined point, the magnetic pull by the solenoid upon core 45 would be insufficient to counter-balance 100 spring 47, and lever 44 would be tilted in the opposite direction to render the other set of pawls effective to move the negative carbon away from the positive carbon until the voltage reaches the predetermined point. 105

When the tip of the positive electrode moves away from the focal point of the reflector, the rays of light will be concentrated by a lens 111 to pass through an aperture 112 in the thermostat and strike upon the 110

thermostatic strip 113. The latter strip will buckle more readily than strip 114, which is shielded by strip 113, and thus bring contact 115 into engagement with contact 116, thereby closing a circuit through electromagnet 117. Said electromagnet thus energized swings an armature 118 pivoted at 119 so that rod 50 is moved upwardly into openings 120 in a collar 121. Said collar when 10 rod 50 is in lowered position, normally is in frictional engagement with a gear 53 which is constantly rotated through gear 52, shaft 51 and gearing within the control box, by motor 100. The collar 121 is provided with 15 an internal thread 125 with which meshes a gear 126 mounted upon the hub 127 of gear 53, said gear 126 being fixed to a shaft 128 to the opposite end of which is fixed a pinion 129 meshing with a gear 130 fixed 20 upon a shaft 131 to which is also fixed on feed roller 132. Said feed roller 132 and a cooperating feed-roller 133 are carried by arms 134 and 135 pivotally mounted on the hub 127 of gear 53 and pressed into engagement 25 with the positive electrode by a spring 136. Gear 130 meshes with a gear 137 fixed to the shaft 138 to which feed-roller 133 is attached.

It will be apparent from the above description that if gear 126 is rotated, gear 129 will also be rotated to rotate in opposite directions gears 130 and 137, and hence, rollers 132 and 133. While collar 121 moves with gear 53 all of the hereinbefore mentioned gears and rollers will be carried thereby and there will be no movement of gears 126 and hence of the rollers relative to the collar. But if the collar 121 is held while gear 53 rotates, the gear 126 will travel 40 around the thread 125 and will be rotated about the axis of shaft 128 to rotate the feed-rollers in opposite directions about the axes of their shafts. The thread 125 is so disposed that gear 126 will be operated to rotate the feed-rollers in a direction to feed the positive carbon to the focal point. As long as the rod 50 engages in one of the openings 120 in the collar 121, gear 126 will rotate and the feed-rollers will feed the positive carbon forwardly. When the positive carbon reaches the focal point, the rays of light from said carbon will not be concentrated by lens 111 to pass through opening 112, and hence strip 113 will not be energized to cause closing of the circuit by contacts 115 and 116. The circuit will thus be broken, the magnet 117 will be de-energized to release armature 118 and cause rod 50 to drop out of engagement with the openings 60 in collar 121. No further feeding of the positive carbon will take place until the tip thereof burns away from the focal point.

From the above description it will be apparent that the negative electrode is fed toward or away from the positive, in accord-

ance with variations in potential across the arc, and that the forward end of the positive electrode is maintained at a predetermined point by the thermostat-controlled mechanism. If the rear end of the positive electrode should pass beyond and leave the feeding rollers, the thermostat controlled mechanism would still function to rotate the rollers in a direction for feeding the positive carbon inwardly to maintain the inner end 70 of the positive carbon at the predetermined point, but the carbon having left the rollers, the latter will rotate without feeding the positive carbon. At the same time the negative feed would continue to maintain the arc. 80 This results in the inner end of the positive carbon burning into the head and injuring the mechanism therein. To prevent such an occurrence the head 18 is provided with a contact 60 positioned outwardly of the rollers 85 in said head and adapted to bring into action means for extinguishing the arc when the carbon becomes too short. Said contact preferably forms part of the shunt circuit which includes the solenoid 46. It will be apparent 90 that as soon as the outer end of the positive carbon passes inwardly beyond contact 60, and before it has left the rollers, the circuit through solenoid 46 will be broken, spring 47 will no longer be counterbalanced and a 95 set of pawls will be brought into contact with the corresponding ratchet-wheel to feed the negative carbon outwardly, thus lengthening the arc, increasing the arc potential and finally extinguishing the arc. Also 10 shunted across the main lines 61 and 62 is a circuit-breaker indicated diagrammatically at 64 and operated by a high voltage coil 65. The latter is designed not to function when the arc potential is of a certain, normal 10 predetermined value, but upon a predetermined increase in arc potential it will operate the circuit-breaker to break the circuit of the motor 100 and the other feed operating mechanism and also the arc circuit. Hence, when 11 the outward end of the positive carbon passes beyond the contact 60 and the negative carbon is operated outwardly to increase the arc potential, the high-voltage coil will, when the predetermined increase in potential has been effected, operate the circuit-breaker. While the circuit through the arc may be broken at the arc before the circuit breaker opens, the circuit-breaker is desirable for at 12 least two reasons, first, it will break the arc before the negative has fed back too far so as to endanger the reflector 101 and second it breaks the circuit of the motor 100 to stop the feed which the breaking of the circuit at the arc does not do. The circuit-breaker device is rendered effective or ineffective at will by a switch 67. While a two-pole circuit-breaker has been illustrated, it will be understood that a single-pole circuit-breaker 13 may be used if desired.

If the negative carbon is consumed until its outer end leaves the rollers in head 17, the arc will lengthen, since the inner end of the positive carbon is held in constant position, and the arc potential will increase until it is extinguished at the arc or until the high-voltage coil operates the circuit-breaker. The device will, of course, function also in the exceptional case where both carbons leave the respective feed rollers substantially simultaneously.

The head 18 comprises, in addition to the parts 140 and 141 in which are contained the feed-rollers and the actuating mechanism associated therewith, a nose-piece 145. The part 141 is provided with a hub portion 146 which extends forwardly into the nose-piece from which it is insulated by insulating material 147. The hub portion 146 extends over the hollow support 16 through which air is blown from a blower or fan 150 and distributed around said hub portion by fins or baffles 151 fixed thereto to cool the electrode and holder. The air issues through an aperture 152 in the nose piece. The portion of the nose piece in front of insulating material 147 is provided with a bore through which the positive electrode extends and with an annular chamber 155 surrounding said bore. The bore is insulated from the electrode by a dead air space 153.

In order to prevent diffusion of the light issuing from the negative electrode, the nose piece 145 may be provided with a light-gathering peripheral extension or screen 160 formed preferably integral therewith. The screen diverges in a direction opposite to that of the rays of light issuing from the negative electrode and since it is positioned near the negative electrode, it will effectively intercept the rays of light issuing from the negative electrode.

In accordance with the provisions of the patent statutes, I have herein described the principle of operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having herein described my invention what I claim and desire to secure by Letters Patent is:

1. The combination with an arc lamp having a pair of electrode holders and means for feeding an electrode through each holder, of means controlled by the position of the outer end of one of the electrodes with

respect to its holder for breaking the arc circuit.

2. In an arc lamp adapted to employ a pair of electrodes, means controlled by the arc potential for breaking the circuit. 70

3. In combination with an electric arc lamp adapted to employ a pair of electrodes, a circuit-breaker in the lamp circuit, and a coil connected across said circuit for actuating said circuit-breaker when the potential drop across the arc reaches a predetermined 75 value.

4. The combination with an arc lamp having a pair of electrode holders and means for feeding each electrode through its holder, 80 of means for withdrawing one of said electrodes to lengthen the arc and increase the arc potential when the other electrode stops feeding, and means for automatically breaking the feed circuits when the potential drop 85 across the arc reaches a predetermined value.

5. The combination with an arc lamp having a pair of electrode holders and means for feeding an electrode through each holder, said means comprising feed-rollers engaging said electrodes, of means controlled by the length of one of said electrodes for automatically breaking the arc circuit before said outer end reaches its feed-rollers. 90

6. The combination with an arc lamp having a pair of electrode-holders and means for feeding an electrode through each holder, said means comprising feed rollers engaging said electrodes, of means controlled by the position of the outer end of one of 100 said electrodes with respect to its holder, before said outer end reaches its feed-rollers, for feeding the other electrode backwardly to lengthen the arc and increase the arc potential, and means for automatically breaking the circuit when the potential drop 105 across the arc reaches a predetermined value.

7. The combination with an arc lamp having a pair of electrode holders and means for feeding a positive electrode through one of said holders and a negative electrode through the other of said holders, said means comprising feed-rollers engaging said electrodes, of means controlled by the position of the outer end of the positive electrode with respect to its holder, before said outer end reaches its feed-rollers, for feeding the negative electrode backwardly to lengthen the arc to extinguish the same, and other means for automatically breaking the lamp circuit at 115 such time.

8. The combination with an arc lamp having a pair of electrode holders and means for feeding an electrode through each holder, 120 said means comprising feeding means engaging said electrodes, of means controlled by the length of one of said electrodes, before said outer end reaches its feed-rollers, for feeding the other electrode backwardly to 125 130

lengthen the arc, a circuit-breaker in the lamp circuit, and a voltage coil connected across the circuit for actuating said circuit-breaker when said arc is extinguished or the 5 potential drop thereacross reaches a predetermined value.

9. The combination with an arc lamp having a pair of electrode holders and means for feeding an electrode through each holder, 10 said means comprising an electromagnet, and feed-rollers engaging said electrodes, of a contact in the circuit of said magnet and positioned so that the outer end of one of said electrodes engages said contact before 15 engaging its feed-rollers, the circuit through said magnet being broken when said outer end passes beyond the contact, means whereby the breaking of the circuit through said magnet by said outer end feeds the other 20 electrode backwardly to lengthen the arc to extinguish the same and increase the arc potential.

10. The combination with an arc lamp having a pair of electrode holders and means 25 for feeding a positive electrode through one of said holders and a negative electrode through the other of said holders, said means comprising an electromagnet, and feeding rollers engaging said electrodes, of a contact 30 in the circuit of said magnet and positioned outwardly of the positive feed-rollers, so that the outer end of the positive electrode engages and passes beyond said contact before

engaging the positive feed-rollers, the circuit through said magnet being broken when 3 the outer end of the positive electrode passes beyond said contact, means whereby the breaking of the circuit through said magnet operates the negative electrode outwardly to 4 lengthen the arc and additional means responsive to the lengthening of the arc for automatically breaking the lamp circuit.

11. The combination with an arc lamp having a pair of electrode holders and means for feeding an electrode through each holder, 4 of means controlled by the position of the outer end of one of the electrodes for extinguishing the arc and rendering inoperative the feeding means.

12. In an arc lamp adapted to employ a 5 pair of electrodes, means for feeding the electrodes and means controlled by the arc potential for extinguishing the arc and stopping the feeding means.

13. In an arc lamp adapted to employ a 5 pair of electrodes, of means for feeding one electrode to position, means for advancing or retracting the other electrode in accordance with the arc length, and means for causing 6 said last named means to retract said electrode to extinguish the arc when said first named means is about to cease to function.

In testimony whereof I have affixed my signature.

MARTIN L. PATTERSON.
